ATTORNEYS

UNITED STATES PATENT OFFICE.

JAMES DELNO FORD, OF SOMERSET, OHIO.

GOLD-LEAF CONDENSER.

SPECIFICATION forming part of Letters Patent No. 767,744, dated August 16, 1904.

Application filed May 16, 1904. Serial No. 208,144. (No model.)

To all whom it may concern:

Be it known that I, JAMES DELNO FORD, a citizen of the United States, residing at Somerset, in the county of Perry and State of Ohio, have made certain new and useful Improvements in Gold-Leaf Condensers, of which the following is a specification.

My invention is an improvement in dental appliances, being in the nature of a condenser for the gold-foil used in fillings; and the invention consists in certain novel constructions and combinations of parts, as will be herein-after described and claimed.

In the drawings, Figure 1 is a perspective view of an apparatus embodying my invention. Fig. 2 is a vertical longitudinal section of the same. Fig. 3 is a detail perspective view of one of the sections of the apparatus. Fig. 4 is a detail perspective view of the other section of the apparatus. Fig. 5 is a sectional view showing the parts inverted from the position shown in Fig. 2, and Fig. 6 shows a somewhat-different form of stop for limiting the degree to which the gold may be condensed.

It is deemed desirable in many instances to form the leaf of gold-foil into a bar, and frequently it is desired to make the bars in different sizes; and one object of my invention is to provide the one apparatus which can be utilized for producing two sizes of bars and which can be utilized in producing more than two sizes of bars by providing extra sections of the form shown in Fig. 4 of the accompanying drawings. In securing these results I provide a condenser which comprises two sections slidable relatively to each other and provided with opposing shoulders and means for varying the exposed or operating surface of one of the shoulders, whereby it may be conformed to the extent of the opposing shoulder, and in the construction shown I arrange for operating the means for varying the exposed or operating surface of one shoulder by the other shoulder, as will be more fully described.

As shown, the apparatus comprises a section A, as shown in Fig. 3, and a section B, as shown in Fig. 4, these sections carrying the

shoulders which oppose each other in the operation of condensing the gold. The section A comprises a base-plate A', provided at about its middle with an upwardly-projecting transversely-extending flange A², forming the shoulder which co-operates with the shoulder on the section B in the operation of condensing the gold. The section A also has at the opposite edges of the base-plate A' upwardly-extending side plates A³, which form rails on which the section B slides, as well as operate to retain the leaf of gold-foil in the condensing operation. As shown, the side flanges A³ incline upwardly from one end, a³, toward the shoulder-flange A² and extend thence at a uniform height to their opposite ends, a'. A spring packing-plate A⁴ is held at one edge, a⁴, to the base-plate A' and is movable at its other edge, a⁵, close to the operating-surface of the shoulder or flange A², resting normally in the position shown in full lines, Fig. 2, near the upper edge of said shoulder and adapted to be depressed to the position indicated in dotted lines in said Fig. 2 by the operating-shoulder of the slide B, as will be understood from the dotted lines in said Fig. 2. By this means the spring packing-plate is moved relatively to the operating-shoulder of the section A in such manner as to vary the exposed or operating surface of such shoulder, whereby I am able to secure by the use of the section A and a proper co-operating section or sections bars of different sizes from the leaves of foil-gold. This idea of varying the exposed or operating surface of one of the shoulders in order that it may conform to the extent of the opposing shoulder is an important feature of my invention, and I find in practice that it operates to advantage with an operating-section, such as shown in Fig. 4 of the drawings. This section B has a body or handle portion B', made of a length to rest at its ends upon the side flanges A³ of the section A, and has at its opposite edges the projecting flanges B² and B³, one of which forms a shoulder to oppose the shoulder A² of the section A in the operation of the invention, while the other or opposite flange B² or B³, operating between the side flanges A³ between

the flange A^2 and the edge a' of the base-plate A' , aids in guiding the section B in its movements relatively to the section A from the position shown in full lines, Fig. 2, to 5 the position indicated in dotted lines in the same figure. It will also be noticed that I make the flanges B^2 and B^3 of different heights, so that the flange B^2 may be adjusted to serve as one of the operating-shoulders to produce 10 in connection with the flange A^2 a bar of a given size, while the shoulder B^3 may be employed for producing a larger bar, if desired, and by providing two or more sections B with flanges of different heights bars of any 15 desired size may be produced.

In operation the leaf may be placed on the spring packing-plate A^4 and the section B be applied, as shown in Fig. 2, and then moved from the positions shown in full lines 20 in said figure to that indicated in dotted lines, when the shoulder B^3 , opposing the shoulder A^2 , will condense the gold into a flat bar of a width equal to the height of the shoulder B^3 , the spring packing-plate yielding to the pressure of the shoulder B^3 and being depressed thereby to the dotted-line position shown in 25 Fig. 2, it being understood that the packing-plate will readily adjust by its resilience to the full-line position shown in Fig. 2 when 30 the pressure of the slide B is removed.

It is preferred to curve the ends of the flanges B^2 and B^3 slightly inward at b^2 and b^3 , as best shown in Fig. 4. The purpose of 35 curving the ends of the flanges B^2 and B^3 is to prevent the complete condensing of the gold, as well as to regulate the degree to which the gold is condensed. By turning the ends out straight the gold may be condensed to a greater degree, while by bending such ends 40 in the complete condensing of the gold may be perfected and the degree to which the gold is condensed may be regulated to suit the operator. Similar results might be secured by providing set-screws at the opposite ends of 45 the flange A^2 , as will be understood from Fig. 6 of the drawings.

The apparatus may preferably be employed in the arrangement shown in Fig. 2, or may be inverted to the position shown in Fig. 5, 50 in which the section A is uppermost.

Having thus described my invention, what I claim as new, and desire to secure by Letters Patent, is—

1. A gold-leaf condenser comprising two 55 sections slideable relatively to each other and provided with opposing shoulders and means for varying the exposed or operating surface of one of the shoulders, whereby it may be conformed to the extent of the opposing 60 shoulder.

2. A gold-leaf condenser comprising two sections slideable relatively to each other and having opposing shoulders and means arranged for operation by one of the shoulders

whereby to vary the exposed or working surface of the other shoulder. 65

3. A gold-leaf condenser comprising two sections slideable one along the other, and having opposing shoulders, one of the sections having a spring packing-plate which is pressed 70 upon and arranged to be compressed by the shoulder of the other section.

4. A gold-leaf condenser comprising two sections slideable one along the other, and provided with means for condensing the gold and 75 with a spring packing-plate.

5. A gold-leaf condenser comprising two sections slideable relatively and provided with opposing shoulders and a spring packing-plate which is pressed upon and arranged to be operated by one of the opposing shoulders. 80

6. A gold-leaf condenser comprising two sections slideable relatively to each other and provided with opposing shoulders and means on one of the shoulders for limiting the extent to which the gold may be condensed. 85

7. A gold-leaf condenser consisting of a section having a base-plate, side flanges and a transverse operating-shoulder and a spring packing-plate operating at its movable edge 90 adjacent to said operating-shoulder, and a second section bearing against the side flanges of the first section and having a shoulder opposing that of the first section and arranged to operate the spring packing-plate, substantially as set forth. 95

8. A gold-leaf condenser, comprising a section having a transverse operating-shoulder and side flanges, and a section having a shoulder to oppose the shoulder of the first section 100 and also provided with a second shoulder operating as a guide for its section in the operation of condensing the gold.

9. In a gold-leaf condenser, a section comprising a base-plate, a transverse operating-shoulder thereon, and a spring packing-plate movable alongside said shoulder, whereby the exposed or operating surface of the shoulder may be varied to conform to the extent of an 105 opposing shoulder. 110

10. An apparatus comprising a section having a shoulder against which the gold may be condensed, and a second section comprising a body portion and opposite shoulder portions on said body portion, and adapted to be operated in connection with the shoulder of the first section, substantially as set forth. 115

11. In a gold-leaf condenser, a section provided with a flange adapted to serve as an operating-shoulder and having its ends turned 120 inwardly, and a section having a shoulder to co-operate with said first section, substantially as set forth.
